CLAIM

I claim the ornamental design for a bicycle frame, as shown and described.

DESCRIPTION

FIG. 1 is a top, front, and right side perspective view of a bicycle frame embodying my new design;

FIG. 2 is a right side elevation view thereof;

FIG. 3 is a left side elevation view thereof;

FIG. 4 is a rear elevation view thereof;

FIG. 5 is a front elevation view thereof;

FIG. 6 is a top plan view thereof;

FIG. 7 is a bottom plan view thereof; and,

FIG. 8 is a top, rear, and right side perspective view thereof.

The broken lines in the drawings illustrate portions of the bicycle frame which form no part of the claimed design.
